UNITED STATES PATENT OFFICE.

ALEX BODNER, OF DUQUESNE, PENNSYLVANIA.

DUMPING-CAR.

1,168,847.

Specification of Letters Patent. Patented Jan. 18, 1916.

Application filed March 26, 1915. Serial No. 17,269.

To all whom it may concern:

Be it known that I, ALEX BODNER, a citizen of the United States, residing at Duquesne, in the county of Allegheny and State 5 of Pennsylvania, have invented a new and useful Dumping-Car, of which the following is a specification.

The present invention appertains to ladle dumping cars, of the type disclosed in the 10 patent to E. C. Sherman *et al.*, No. 1,014,612, issued January 9, 1912.

A salient feature of the invention is the provision in a ladle dumping car, of means for locking the ladle in upright position, 15 whereby the same cannot be accidentally dumped to one side or the other, and said means being operable to allow the ladle to be dumped to one side or the other without the liability of the ladle dumping otherwise 20 than as desired by the operator.

Another object of the invention is the provision of a locking mechanism of the nature indicated, which is adapted to operate the pressure fluid valve of the cylinder, whereby 25 the valve will be operated properly according to the side to which the ladle is to be swung. In other words, the construction of the present mechanism is such that when the locking means is operated to allow the 30 ladle to dump to one side, the controlling valve is operated automatically to allow the pressure fluid to flow into the proper end of the cylinder; so that when the pressure fluid is turned on it will move the ladle to the 35 proper side to dumping position.

Another object of the invention is the provision of novel means for operatively connecting the cross head and the adjacent trunnion of the ladle ring or carrier, whereby 40 the trunnion will be properly rolled upon its support when the cross head is reciprocated, for tilting the ladle ring or carrier effectively.

With the foregoing and other objects in 45 view which will appear as the description proceeds, the invention resides in the combination and arrangement of parts and in the details of construction hereinafter described and claimed, it being understood that 50 changes in the precise embodiment of the invention herein disclosed can be made within the scope of what is claimed without departing from the spirit of the invention.

The invention is illustrated in the accompanying drawings, wherein:

Figure 1 is a fragmental end view of a

ladle dumping car embodying the present improvements. Fig. 2 is a vertical section taken approximately on the line 2—2 of Fig. 1. Fig. 3 is a sectional view of the line 3—3 of Fig. 2. Fig. 4 is a detail view taken on the line 4—4 of Fig. 2. Fig. 5 is a sectional view taken on the line 5—5 of Fig. 2. Fig. 6 is a sectional detail of the controlling valve. Fig. 7 is a plan view of the controlling valve. Fig. 8 is a detail view in plan of the means for attaching the extension and piston rod. Fig. 9 is a detail view illustrating a fragmental portion of the slide and latches for holding the same.

Inasmuch as the present improvements are employed on the common ladle dumping car, as disclosed in the said patent, *supra*, it is not deemed necessary to illustrate or describe the general or complete construction 75 of the car, since reference may be had to the said patent, and ladle dumping cars have become so well known in practice, that the application of the improved features thereto will be readily understood by those skilled in 80 the art, it is thought.

The fragmental portion of the ladle dumping car depicted in the drawing, illustrates a portion of the frame 1 of the car, and a portion of the ring or carrier 2 in 85 which the ladle (not shown) is seated. This ring or carrier 2 has trunnions rolling upon the frame 1, only one of the trunnions, designated 3, being illustrated. This trunnion 3 is the one that is actuated for moving the 90 ring or carrier 2, and rolls upon a horizontal support or rail 4 of the frame 1, and which is provided with a rack 5. The trunnion 3 is provided with a gear segment 6 engaging the rack 5, whereby the trunnion 95 3 is constrained to roll properly upon the transverse support or rail 4. The actuating mechanism for tilting the ring or carrier 2 includes a pair of standards 7 projecting upwardly from the frame 1 at the opposite 100 ends of the support or rail 4, and a pair of vertically spaced transverse guide rods 8 terminally attached to the standards 7, and having the cross head 9 mounted for sliding movement thereon. The cross head 9 is provided with an extension 10 projecting toward one side, and having its end secured or pivoted to the outer end of the piston rod 11 which is attached at its other end to the piston 12 which reciprocates within the 110 transverse cylinder 13 supported by the frame 1.

In order to operatively connect the trunnion 3 and cross head 9, the face or end of the trunnion 3 is provided above and at the opposite sides of its center with outstanding pins or lugs 14 which project or engage into a pair of grooves or channels 15 provided in the adjacent side of the cross head 9. The grooves 15 have the straight vertical upper portions 16, and the converging 10 curved lower portions 17 have their lower ends open. When cross head 9 is reciprocated transversely along its guide, the pins 14 of the trunnion 3 being engaged to the grooves 15 of the cross head, will cause the 15 ladle ring or carrier 2 to tilt properly toward one side or the other, and when the cross head 9 is in neutral or intermediate position, the ring or carrier 2 will be held horizontal for holding the ladle upright. Referring to Fig. 3, supposing the cross head 9 is moved to the left, the right hand pin 14 will be engaged by the right hand wall of the respective groove 15, and the right hand pin 14 being moved to the 20 left with the cross head 9 will roll the trunnions of the ring or carrier 2 to the left, and the ring or carrier will thus be properly tilted to the left, the left hand pin 14 swinging downwardly along the curved portion 25 17 of the respective groove. When the right hand pin 14 reaches the upper end of its groove 15, the tilting movement of the ladle ring or carrier will be stopped. The converse is true when the cross head is 30 moved in the opposite direction. The inter-engaging portions of the trunnion 3 and cross head 9 will serve to effectively move the ladle ring or carrier when the cross head is reciprocated, and the ladle ring or carrier will be held steady at any position 35 thereof.

The end portions of the cylinder 13 are connected by means of the respective pipes 18 and 19 to a controlling valve 20 to which the pressure fluid supply pipe 21 is connected. This pipe 21 has a controlling valve 22 for establishing and cutting off the flow of pressure fluid to the cylinder 13. The valve 20 is operable in the ordinary manner, to allow the pressure fluid to flow into the cylinder 13 through one of the pipes 18-19 and to flow out of the other end of the cylinder through the other of the said pipes, when the valve 20 is set at one position, and to allow the pressure fluid to flow into and out of the opposite ends of the cylinder when the valve 20 is reversed. Since the valve 20 is of ordinary construction, it is not necessary to illustrate or describe the 40 same in detail.

The locking mechanism co-operates with a depending stop flange 23 carried by the cross head 9, and embodies a pair of latch devices. These latch devices embody rock 45 shafts 24 and 25 journaled in suitable bear-

ings 26 carried by the frame 1, and having secured thereon the respective latches 27 and 28. The rock shafts 24 and 25 are provided at their remote ends with handles 29 and 30, respectively, and the latches 27 and 28 are provided with arms or portions 31 adapted to swing against or over the ends of the flange 23 of the cross head. The latches 27 and 28 are provided with oppositely projecting arms 32 having curved ends 75 32a.

A mechanism is employed for holding one or both of the latches 27-28 in engagement with the stop flange 23 of the cross head, and to this end, a transverse reciprocatory rod 33 is slideable through suitable bearings 34 carried by the frame 1, and is provided adjacent the latches with angularly extending detents 35 against which the curved ends 32a of the latch arms 32 are adapted to bear ordinarily. The rod 33 is provided with suitable collars or stops 36 co-operating with the bearings 34 for limiting the reciprocatory movement of the rod 33 properly. The respective parts are so arranged that when the rod 33 is moved to the left to the dotted line position, as seen in Fig. 5, the left hand detent 35 will be disengaged from the left hand latch 27, while the right hand detent 35 will still be engaged to the right hand latch 28, for allowing the left hand latch 27 to be released from the cross head, while the right hand latch 28 is held in active position. Conversely, when the rod 33 is moved to the right, to the dotted line position illustrated in Fig. 1, the right hand detent 35 is disengaged from the right hand latch 28, while the left hand detent 35 is still in engagement with the left hand latch 27 to hold the left hand latch in action position. When the rod 33 is at a neutral or intermediate position, both of the detents 35 will be engaged to the latches for holding the latches in active position.

The rod 33 is operatively connected with the valve 20, whereby the reciprocation of the rod will actuate said valve. The operative connection embodies a vertical rock shaft 37 carried by the frame in any suitable manner, and having an angularly extending arm 38 adjacent its lower end working in the slotted portion 39 of the rod 33. The valve 20 embodies a casing 40, as seen in Fig. 6, to which the pipes 18, 19 and 21 are connected, and a valve member 41 is rotatable within the casing 40 and has a pair of passages 42-43. The casing 40 has a port 44 leading to the atmosphere, and the valve member 41 has a slotted arm 45 in which a second arm 46 of the shaft 37 works. The parts are so arranged, that when the rod 33 is moved to the left, as viewed in Fig. 1, the arm 38 is swung to the left, and the arm 46 being swung similarly, will swing the arm 45 to the position illustrated in Fig. 6. This 130

will cause the passage 42 of the valve member 41 to connect the pipes 18-21, while the passage 43 connects the pipe 19 with the port 44. The pressure fluid will therefore flow from the pipe 21 through the pipe 18 into one end of the cylinder, while the pressure fluid will flow from the other end of the cylinder through the pipe 19 to the atmosphere. When the rod 33 is moved to the right, as viewed in Fig. 1, the shaft 37 will be rotated in the opposite direction, so that the arm 46 swings to the right, to correspondingly swing the valve member 41. The passage 42 will now connect the pipes 19 and 21, and the passage 43 will connect the pipe 18 with the port 44, so that the piston is operated in the opposite direction, as will be apparent.

In operation, when the ladle ring or carrier 2 is in neutral or normal horizontal position, the piston 12 will be disposed intermediate the ends of the cylinder 13, and the cross head 9 will stand between the ends of its guide. The flange 23 of the cross head will then lie between the latches 27 and 28, and the handles 29 and 30 of the latches may be swung to swing the arms 31 of the latches across the ends of the flange 23. The rod 33 is then moved to neutral or intermediate position so that the detents 35 thereof will hold the latches 27 and 28 in operative position, and the flange 23 of the cross head lying between the latches, will prevent the cross head from reciprocating or sliding. This will lock the ladle ring or carrier in neutral or normal position, so that there will be no liability whatever for the ladle to be dumped or discharged accidentally.

Now, supposing it is desired to dump the ladle to the right, as seen in Fig. 1, the rod 33 is moved to the right as to release the right hand latch 28, and the right hand latch 28 may then be swung out of engagement with the flange 23. The right hand latch 28 is thus swung out of the path of the flange 23, and the valve 20 is set so that the pressure fluid can flow from the supply pipe 21 through the pipe 18 into the left hand end of the cylinder 13. Consequently, when the valve 22 is opened, the piston 12 will be moved to the right, the pressure fluid being discharged from the right hand end of the cylinder 13 through the pipe 19, and the cross head 9 will be moved to the right, so as to dump the ladle correspondingly. The left hand latch 27, in the meantime, is still locked in active position, and when the ladle is emptied and returned to normal position, the flange 23 of the cross head will strike against the latch 27 to limit the movement of the cross head when it reaches its normal or neutral position. The latch 28 may then be swung to active position, for holding the cross head in place, and the rod 33 is then moved to normal or neutral position for

holding the latch 28 as well as the latch 27 in active position.

Supposing that it is desired to dump the car to the left, as seen in Fig. 1, the rod 33 is moved to the left, so as to release the left hand latch 27, and to so set the valve 20 as to bring the supply pipe 21 into communication with the pipe 19, and to open the pipe 18 to the atmosphere. The latch 27 is then swung out of engagement from the flange 23, and the valve 22 is then opened so as to force the piston 12 to the left, for dumping the ladle to the left side. When the ladle is emptied and returned to normal position, the cross head 9 will be moved back against the right hand latch 28, and the left hand latch may then be swung to active position to hold the cross head in place, and after which the rod 33 may be moved to neutral position for locking both of the latches in active position.

The latches 27 and 28 swing counter clockwise, as seen in Fig. 2, when they are disengaged from the cross head, and since the detents 35 normally engage the ends 32^a of the arms 32 of the latches, the detents will prevent the latches from swinging to released positions.

From the foregoing, taken in connection with the drawings, it is believed that the advantages and attributes of the invention will be apparent without further comment being necessary.

What is claimed is:

1. In a dumping car, a tilting member, a reciprocatory member operatively connected thereto and movable in either direction for tilting the tilting member in one direction or the other, and a pair of latches, the reciprocatory member being normally disposed between said latches so that it cannot move in either direction, the latches being independent so that either one can be released from said reciprocatory member to allow said member to move in one direction.

2. In a dumping car, a tiltable member, a reciprocatory cross head operatively connected thereto and movable in either direction from a neutral position to tilt said member in one direction or the other, and a pair of oscillatory latches, said cross head being normally disposed between said latches to prevent the movement of the cross head in either direction, the latches being adapted to be swung independently away from said cross head, whereby when one latch is released, the cross head can move in one direction, and when the cross head is returned to neutral position it will strike the other latch.

3. In a dumping car, a tilting member, a cross head operatively connected thereto for tilting the same, a pair of latches operable independently, said cross head being normally disposed between said latches to be

held against movement in either direction, and detent means coöperable with the latches and operable for holding one or both of the latches in operative position.

5. 4. In a dumping car, a tilting member, a cross head operatively connected thereto for tilting the same, a pair of devices one of which is arranged to prevent the movement of the cross head in one direction and the 10 other of which is arranged to prevent the movement of the cross head in the other direction, and means whereby one of said devices is always held in active position and whereby both of said devices can be held 15 in active position.

5. In a device of the character described, a tilting member, a sliding member operatively connected thereto, a cylinder, a piston working within the cylinder and connected to said sliding member, means for allowing pressure fluid to be admitted into and discharged from the opposite ends of the cylinder, a pair of devices coöperable with the sliding member, one of said devices 20 being arranged to prevent the said member from moving in one direction while the other device is arranged to prevent the said member from moving in the other direction, and means coöperable with said devices for 25 always holding one of them in active position and arranged to hold both of said devices in active position, the last mentioned means being operatively connected to the aforesaid means, whereby when one of said 30 devices is released, the first mentioned means will be operated to permit the pressure fluid to flow into the respective end of the cylinder.

6. In a device of the character described, 40 a tilting member, a sliding member operatively connected thereto, a pair of oscillatory latches adapted to swing over the ends of the sliding member, and a reciprocatory member having detents coöperable 45 with the latches whereby when the reciprocatory member is in one position, the detents thereof will hold the latches in operative position, and when the reciprocatory member is moved in one direction or the 50 other, one or the other of the detents will be released from the respective latch to allow the latch to be released from the cross head.

7. In a device of the character described, 55 a tilting member, a cross head operatively connected thereto, a cylinder, a piston working within the cylinder and connected to the cross head, controlling means for allowing pressure fluid to flow into and out of

the opposite ends of the cylinder, a pair of 60 latches coöperable with the cross head, one of the latches being arranged to prevent the movement of the cross head in one direction, the other latch being arranged to prevent the movement of the cross head 65 in the other direction, and a detent device coöperable with the latches for holding one or both of the latches in active position, the detent member being operatively connected to said controlling means whereby when the 70 detent member is moved to release one of the latches, the controlling means will be set to permit the pressure fluid to flow into the respective end of the cylinder.

8. In a device of the character described, 75 a tilting member, a cross head operatively connected thereto, a cylinder, a piston working within the cylinder and connected to the cross head, controlling means for allowing pressure fluid to flow into and out of 80 the opposite ends of the cylinder, a pair of oscillatory latches adapted to be swung across the opposite ends of the cross head, a reciprocatory rod having detents coöperable with the latches for holding one or both of 85 the latches in operative position, and an operative connection between the rod and controlling means whereby when the rod is moved in one direction to release one of the latches, the controlling means will be set to 90 permit the pressure fluid to flow into the respective end of the cylinder.

9. In a dumping car, a frame having a horizontal rail, a tilting member having a trunnion adapted to roll upon said rail, a 95 cross head having grooves, and the trunnion having pins working in said grooves, whereby when the cross head is reciprocated it will roll the trunnion upon the rail.

10. In a dumping car, a horizontal rail, a 100 tilting member having a trunnion adapted to roll upon said rail, the end of the trunnion having a pair of outstanding pins above and at the opposite sides of the center of the trunnion, and a sliding cross head 105 having a pair of grooves receiving said pins, the grooves having straight vertical upper portions and lower curved converging portions, whereby when the cross head is reciprocated it will properly roll the trunnion 110 upon the rail.

In testimony that I claim the foregoing as my own, I have hereto affixed my signature in the presence of two witnesses.

ALEX BODNER.
